BUILDING

Kenneth C. Johnson, Covina, Calif., assignor to Amigos Restaurants, Inc., Glendale, Calif., a corporation of California

Filed Mar. 24, 1969, Ser. No. 16,392

Term of patent 14 years

Int. Cl. D25—04

U.S. Cl. D13—1

FIG. 1 is an elevation of one face of a building according to the invention; and

FIG. 2 is an elevation of an adjacent face of the building.

The rear and side not shown are plain and the building is rectangular.

I claim:

The ornamental design for a building, as shown and described.
